UNITED STATES PATENT OFFICE.

GUY HILL, OF WASHINGTON, DISTRICT OF COLUMBIA, ASSIGNOR OF ONE-HALF TO
LOUIS STEINBERGER, OF BROOKLYN, NEW YORK.

ELECTRICAL CONDENSER.

1,408,738.

Specification of Letters Patent.

Patented Mar. 7, 1922.

Application filed July 23, 1919. Serial No. 312,724.

To all whom it may concern:

Be it known that I, GUY HILL, a citizen of the United States, residing in Washington, District of Columbia, have invented 5 certain new and useful Improvements in Electrical Condensers, of which the following is a specification.

This invention relates to an improved construction of insulation for the metallic supporting plates of a condenser. This construction is applicable either to a variable air condenser or to a fixed air condenser and the same principles also apply if oil is used instead of air between the plates and also 15 if any other dielectric is used.

My invention is particularly valuable when applied to either fixed or variable condensers used in radio telegraph and radio telephone systems, although it is of value 20 for other work.

The main object of the invention is to construct a supporting metallic plate for a condenser having a bushing thereon and insulated therefrom.

25 Another object of the invention is to construct a novel insulating structure by means of which the bushings in the main supporting plates or discs of the condenser are held to and insulated from the plate by a moldable insulating material, to the end that the plate, bushing and insulation will in effect consist in one mechanical unit and thus a substantial and strong construction for building the condenser is obtained.

30 Another object of my invention is to provide such a structure consisting of few parts and simple and inexpensive to manufacture.

Another object of my invention is to obviate the mechanical and electrical defects 40 found in prior structures of this character.

Other objects will appear from the subjoined specification and claims.

Referring to the drawings:

Fig. 1 is a plan view of an electrical condenser provided with a supporting plate for the same embodying my invention, the operative half being removed.

Fig. 2 is a section on line 2—2 of Fig. 1.

Fig. 3 is a section of a fragment of a 50 supporting plate also illustrating my invention.

Fig. 4 is a plan of a supporting plate further illustrating my invention.

Fig. 5 is a section on line 5—5 of Fig. 4.

55 While the illustrations and constructions

shown in the drawing relate more particularly to a variable air condenser, as has been stated above the same principles apply to a fixed air condenser and likewise also apply if oil is used instead of air between the 60 plates, and also when any other dielectric is used.

The structure illustrated is a simple form of variable air condenser with my invention embodied therein. It is therefore only 65 necessary to generally describe the structure of the condenser in order to clearly understand the structure and efficacy of my invention.

Referring to the drawing, the condenser 70 consists of the upper and lower fixed plates A and B constituting the main supporting plates or discs which are held in place by the metal clamping rods 10 which are here conventionally shown, but may be of any 75 approved construction, the plates being secured to the rods by suitable nuts 11. 12 are the fixed plates in electrical contact with the metal rods 10 and 13 are the movable plates in electrical contact with the shaft 20, 80 said plates being properly separated by spacers 14, or any other approved means, not shown, as it does not form a part of this invention. A handle H is secured to the shaft by means of which the shaft may 85 be turned in the bushings acting as bearings.

My invention consists in providing the insulating bushings 30 in the plates A and B within which the shaft 20 is mounted and is adapted to turn. These bushings 30 are 90 insulated from the plates A and B respectively, by a layer of insulation 40, as shown, to secure the bushings 30 in place in the plates A and B. The bushing is first centered in the hole or opening O which is 95 made at a suitable point in the plates A and B respectively. The side of the hole is serrated or roughened in any suitable manner, as at 41, and the outer surface of the bushing is serrated or roughened as at 31 100 so that the insulating material when fixed in place will be more securely held to the plates A and B and to the bushings. After centering the bushing in the opening O, I place the structure in a mold and compress 105 the moldable insulating material under sufficient pressure in the space surrounding the outer surface of the bushing so that the entire strip of insulating material will be held in place and the bushing thus securely, 110

rightly and effectively held in position in the plates A and B, so that there is no possibility of any air space remaining between the walls of the bushing and plate and the insulation, thus preventing brushing and consequent electrical break down.

The insulating material may be any suitable moldable material, preferably that known in the art as electrose.

- 10 The plates A and B so constructed with insulating bushings are put in position in the condenser, as shown, and the shaft 20 is mounted in the bushings in any approved manner. It will thus be seen that the movable plates 13 are insulated from the fixed plates 12 by the two insulations 30, one in each main plate A and B. A substantial mechanical structure is therefore provided and ample insulation is obtained by the construction above described.

15 The size and form of this insulation can be varied as desired.

As illustrated in Fig. 3, the insulation 40 may be provided with an extended surface, 20 thereby increasing the leakage path by means of corrugations consisting of suitable ribs 50 and grooves 51, as shown. So also may the bushing 30 and insulation 40 extend on either side of the plates A and B 25 as at a and b as illustrated, in order to obtain a larger mechanical bearing, when desired.

30 In Figs. 4 and 5 I have illustrated a different form of insulated supporting plates A'. As shown therein, these plates are provided with a plurality of bushings and insulating connections therefor so that the clamping rods 10 can be insulated from the main supporting plates, and these additional insulations 40' are held in the plate 35 A' and to the bushings 30' to secure and hold them in an insulated position in the plate in the same manner as has been previously described.

40 In the construction shown in Figs. 4 and 5 the outer surface of the bushing and the inner surface of the holes O and O' are slightly serrated or roughened so that the moldable insulating material may obtain a 45 secure hold on the metallic surfaces.

From the above description it is therefore very clear that the upper and lower main supporting plates embodying my invention constitute a single practically integral mechanical unit and the electrical and mechanical advantages derived therefrom are superior to those which are present in plates where the bushings are not permanently fixed to the insulation and to the 55 plates. It is also apparent that my invention, consisting as it does of few parts, is simple and inexpensive to manufacture.

60 As changes of construction could be made within the scope of my invention, it is intended that all matter contained in the

above description or shown in the accompanying drawings shall be interpreted as illustrative and not in a limiting sense.

Having now described my invention, what I claim as new and desire to secure by Letters Patent is:

1. In a device of the kind described, a metallic supporting plate for an electrical condenser having an aperture therein, and a bushing secured to the wall of said aperture by a moldable insulating material. 75

2. In a device of the kind described, a metallic supporting plate for an electrical condenser having a hole therethrough, a bushing situated within said hole, and moldable insulating material between the wall of the hole in the plate and the outer wall of the bushing to secure the one to the other. 80

3. A supporting plate or disc for an electric condenser having a hole extending therethrough substantially at the center thereof, and a bushing secured to the wall of said hole by a moldable insulating material. 85

4. A supporting plate or disc for an electric condenser having a hole extending therethrough substantially at the center thereof, a bushing therein, and a strip of moldable insulation tightly fitting therebetween to secure the bushing to the plate. 90

5. A supporting plate or disc for an electrical condenser, a bushing inserted in a hole through the plate and secured thereto by a moldable insulating material so compressed as to tightly fit the metallic parts without permitting air cells therebetween. 95

6. A supporting plate or disc for an electrical condenser provided with a hole extending therethrough, a bushing lining said hole and secured to the plate by compressed moldable insulating material, the joints between the bushing, the plate and the insulating material being free of air holes or cells. 100

7. In a device of the kind described, a supporting metallic plate, a plurality of bushings tightly secured to the plate by moldable insulating material. 110

8. In a device of the kind described, a metallic supporting plate provided with a hole extending therethrough, a bushing fitted in the hole of said plate and of greater length than the thickness of the plate, and tightly and uniformly secured to the plate by moldable insulating material. 115

9. In a device of the kind described, a metallic supporting plate provided with a hole extending therethrough, a bushing fitted in the hole of said plate and of greater length than the thickness of the plate, and tightly and uniformly secured to the plate by moldable insulating material compressed therebetween. 120

10. In a device of the kind described, a metallic supporting plate, a bushing located in a hole extending through the plate, and a strip of moldable insulating material 125

- tightly fitted between the bushing and the plate, the upper and lower surface of the insulation being grooved to extend the leakage surface thereof.
- 5 11. In a device of the kind described, a metallic supporting plate, a bushing located in the center of a hole extending through the plate, and a strip of moldable insulating material tightly fitted between the bushing and the plate, the upper and lower surface of the insulation being grooved to extend the leakage surface thereof, the height of the bushing and the insulation being greater than the thickness of the plate.
- 10 12. In a device of the kind described, a metallic supporting plate having a hole therethrough, a bushing located in the said hole and secured to the wall thereof by a compressed body of moldable insulating material, the opposing walls of the bushing
- and of the hole being serrated to effectively engage with the moldable insulating material.
13. A supporting structure for an electrical condenser having a bushing secured thereto by moldable insulating material.
14. In a device of the kind described, a metallic bushing, a metallic support for an electrical condenser and moldable insulating material intimately connecting the one to the other without permitting air cells therebetween.
- In witness whereof, I have hereunto set my hand at the borough of Manhattan, city and State of New York, this 21 day of July, 1919.

GUY HILL.

In presence of—
ZITA M. GRAHAM.
